DESIGN FOR A CIGARETTE

Kizzie Clay Vinson, Louisa, Ky.

Application July 7, 1943, Serial No. 110,619

Term of patent 3½ years

To all whom it may concern:

Be it known that I, Kizzie Clay Vinson, a citizen of the United States, residing at Louisa, in the county of Lawrence and State of Kentucky, have invented a new, original, and ornamental Design for Cigarette, of which the following is a specification, reference being had to the accompanying drawing, forming part thereof.

I claim:

The ornamental design for a cigarette, as shown.

KIZZIE CLAY VINSON.
